UNITED STATES PATENT OFFICE.

JACOB REICHEL, OF NEW YORK, N. Y.

TROUSERS.

Application filed March 31, 1925 Serial No. 19,591.

This invention relates to knickerbockers, trousers, and the like wearing apparel. One object thereof is to provide in a garment of the character described, improved means whereby the waist-band is made adjustable for a wide range of sizes, which means is normally concealed in part or in whole and yet conveniently arranged for quick and easy operation.

10 A further object of the invention is to provide means of the character described which is inexpensive to embody in the manufacture of wearing apparel, neat in appearance, and to a high degree practical and efficient for the 15 purposes described.

Other objects of this invention will in part be obvious and in part hereinafter pointed out.

The invention accordingly consists in the 20 features of construction, combinations of elements and arrangement of parts which will be exemplified in the construction hereinafter described, and of which the scope of application will be indicated in the following claims.

25 In the accompanying drawing, in which is shown one of the various possible illustrative embodiments of this invention,

Fig. 1 is a perspective view of a pair of trousers constructed to embody the invention;

30 Fig. 2 is a cross-sectional view taken through the waist band of the trouser shown in Fig. 1;

Fig. 3 is a fragmentary perspective view of a modified form of belt construction embodying the invention;

35 Fig. 4 is a fragmentary cross-sectional view taken through the waist band corresponding to the modified form shown in Fig. 3; and

Fig. 5 is a plan view of one of the belt sections.

40 Referring in detail to the drawing, 10 denotes a pair of trousers having an improved adjustable waist-band 11 embodying the invention, said trouser being of any well known construction.

The waist band 11 is seen to comprise the usual outer strip or member 11^a and the inner lining 11^b between which passes belts 12, 13 secured by stitches 14 as shown in Figs. 1 and

50 2. The belt 12 extends around the back and sides of the waist-band 11 and may be formed of a single piece or in two similar parts as shown in Fig. 2, and the belts 13 are positioned to extend from the front trouser closure 10^a about the front and side of the waist-band 11.

Openings 11^c are provided on each side of the waist band member 11^a to permit drawing the corresponding end portions 12^a, 13^a of said belts 12 and 13 respectively to the exterior of 60 the trouser 10 for engaging with a suitable quick-adjusting buckle 15. A pair of slot openings 11^d may also be provided, one on each side of, and adjacent to each opening 11^c wherein the free ends of the belt sections 12 65 and 13 may be inserted as shown in Figs. 1 and 2.

Each of said belts may be made of non-elastic or extensible material as desired, and the end portions 12^a and 13^a of each is preferably shaped to be of less width than the remaining portion so that the latter (the belt section proper) is of substantial width to comfortably fit about the waist of the wearer and so that the adjustable means, namely the end 70 portions 12^a and 13^a and buckle 15 may be made relatively small and inconspicuous.

In using the invention, the trousers 10 are positioned in place and the waist band 11 is adjusted by simply pulling the ends 12^a 80 and 13^a of the belts threaded through the buckle 15 in the well understood manner. The free ends are then inserted in the slot openings 11^d so as not to mar the neat appearance of the garment.

Where it is desired to entirely conceal the adjustment means, the modified form of construction shown in Figs. 3 and 4 may be provided. Here the opening 11^c is made large enough to permit withdrawing the buckle 15 90 from its normal position between the member 11^a and the lining 11^b to the exterior of the trousers for making the adjustment after which said buckle may again be inserted between the said member and lining.

95 It is apparent from the above description that a simple and practical trouser construction is provided embodying improved means whereby the waist size is adjustable, said means being inconspicuously arranged and 100 although permanently incorporated in the trouser structure does not distort or mar the normal appearance of the latter when adjusted to various sizes. Because of the location and shape of the said means, it may be adjusted to comfortably fit about the wearer's 105 waist.

110 It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that 5 all matter herein set forth or shown in the accompanying drawing is to be interpreted as illustrative and not in a limiting sense.

Having thus described my invention, I claim as new and desire to secure by Letters 10 Patent:—

1. A garment of the character described having a waist-band comprising an outer member and an inner lining, a plurality of belts secured to extend between said member 15 and lining, the end portion of each belt being relatively narrow in width, said member being perforated at spaced distances along the waist band to permit the narrow free end portions of the belts to extend to the exterior side of 20 the garment and being also provided with openings on each side of the perforated portions for inserting the narrow free end of the belt.

2. A garment of the character described 25 having a waist-band comprising an outer member and an inner lining, a plurality of belts secured to extend between said member and lining, the end portion of each belt being relatively narrow in width, said member being perforated at spaced distances 30 along the waist band to permit the narrow free end portions of the belts to extend to the exterior side of the garment and being also

provided with openings on each side of the perforated portions for inserting the narrow 35 free end of the belt, and a buckle for engaging with said narrow ends of the belt for adjusting the waist band for various sizes.

3. A garment of the character described 40 having a waist band comprising an outer member and an inner lining in combination with belts secured to extend between said member and lining, said member being perforated at spaced distances along the waist- 45 band to permit the free end portions of the belts to extend to the exterior side of the garment, and being also provided with openings at the side of the perforated portions for inserting the free ends of the belt.

4. A garment of the character described 50 having a waist-band comprising an outer member and an inner lining in combination with means permanently incorporated in the garment structure for adjusting the waist band for various sizes; said means including 55 a plurality of belts secured to extend between said member and lining, said member being perforated at, at least three points spaced along the waist band to permit with- 60 drawing said means to the exterior side of the garment for adjustment purposes and adapted to permit the reinsertion of said means for entirely concealing the same.

In testimony whereof I affix my signature.

JACOB REICHEL.
